INVENTOR.

Charles H. Foster.

BY Ernest L. Tamm

ATTORNEY.

UNITED STATES PATENT OFFICE.

CHARLES H. FOSTER, OF ST. LOUIS, MISSOURI.

REFRIGERATOR DRAIN-TRAP.

1,235,304.

Specification of Letters Patent. Patented July 31, 1917.

Application filed March 29, 1915, Serial No. 17,755. Renewed June 23, 1917. Serial No. 178,630.

To all whom it may concern:

Be it known that I, CHARLES H. FOSTER, citizen of the United States, residing at St. Louis, State of Missouri, have invented certain new and useful Improvements in Refrigerator Drain-Traps, of which the following is a full, clear, and exact description, reference being had to the accompanying drawings, forming a part hereof.

10 My invention has relation to improvements in refrigerator drain-traps; and it consists in the novel construction of trap more fully set forth in the specification and pointed out in the claims.

15 The object of my invention is to provide a drain trap for refrigerators which may be adjusted to the drain pipe of the refrigerator without the necessity of shifting the refrigerator from its assigned position, such 20 adjustments being especially desirable under circumstances where the waste pipe leading to the sewer and which conducts away the water drained from the refrigerator can not be shifted, or where the drain pipe of the 25 refrigerator can not conveniently be brought directly over the collecting basin leading to the waste pipe. Another object of my invention is to construct a drain-trap which can be readily cleaned when occasions therefor 30 arise. The advantages of the invention will be more fully apparent from a detailed description thereof in connection with the accompanying drawings, in which—

Figure 1 is a side elevation of the bottom 35 portion of an ice box or refrigerator, showing my invention applied thereto; Fig. 2 is a side view of the trap, parts being in section; Fig. 3 is a combined rear elevation, and transverse section through the axis of rotation of the collecting basin; and Fig. 4 is a top plan of the trap with parts broken away, and dotted positions showing a partial range 40 of action of the oscillating basin.

Referring to the drawings, R represents 45 a conventional refrigerator, and P the lower end of the drain pipe leading therefrom. In the present embodiment of my invention I provide a waste or sewer pipe 1 projecting through and above the floor F, the upper 50 terminal of the pipe being screw-threaded. Passed over the screw-threaded end of the pipe 1 is an interiorly threaded hollow boss or hub 2 of a collecting basin 3, said boss projecting above the upper surface of the 55 horizontal bottom a of the basin, the bottom a having leading therefrom the inclined

extension bottom b as shown. The bounding walls w, w', leading from said horizontal and inclined bottoms have their upper edges e, e', disposed at an angle conformable to 60 the angle between the bottoms a, b, respectively. Adapted to be deposited over the hub 2 is an inverted cup or cap 4 whose peripheral walls are spaced from the hub, the cup being raised above the upper surface of 65 the bottom a by the ribs 4' formed on the interior surface of the cup walls, the ribs projecting beyond the edges of the cup so as to form feet or props. The cup when thus supported has its lower edge disposed below 70 the upper edge of the hub 2, thereby making a water seal, the surface or level of the water permanently remaining in the basin and forming the seal, being indicated by the dotted line x (Fig. 2).

75 For convenience, the inclined portion of the basin, identified by the inclined bottom b with its inclosing walls w' may be regarded as the "sweep arm" of the basin, the basin proper being restricted to the bottom a and 80 its inclosing walls w. It will be seen from an inspection of Fig. 4, that the basin rotates about the axis of the hub 2 (on the pipe 1) thus causing the sweep arm to oscillate about said axis; and in the event the 85 discharge end of the drain pipe P is out of range or alinement of the waste pipe 1, the basin may be swung around about the axis of the waste pipe until it comes under the pipe P, the water drained from the refrigerator discharging into the trap basin, whence 90 it flows under the cup 4 and over the edge of the boss or hub 2 into the waste pipe 1. Should the trap at any time need cleaning, the cup or cap 4 is lifted off, whereupon access may be had to the portions of the basin around the boss 2, and little time be consumed in cleaning the trap. Once the trap 95 is cleaned, the cup 4 is restored over the boss 2, and the trap is again ready for 100 service.

I do not of course wish to be limited to the precise details here shown as they may be departed from without affecting the nature or spirit of my invention. The screw-threaded connection between the basin and pipe 1 is not indispensable, any other suitable connection permitting the basin to rotate, being within the spirit of my invention. The drain-trap of course is not to be 110 considered as restricted in its application to refrigerators.

Having described my invention what I claim is:

1. A drain-trap having a basin provided with bounding walls, a substantially horizontal bottom portion and an inclined bottom portion leading therefrom and forming a sweep arm therefor, a hollow boss surrounding a discharge opening in the horizontal bottom and projecting above said bottom, and a removable member coöperating with said boss to form a water-seal.

2. A drain-trap having a basin provided with bounding walls, a horizontal bottom portion and an inclined bottom portion leading therefrom and forming a sweep-arm therefor, a hollow boss surrounding a dis-

charge opening in the horizontal bottom, and projecting above said bottom, a removable member coöperating with said boss to form a water-seal, and a fixed hollow member to which the boss may be rotatably secured, whereby the basin may be rotated and the sweep arm thereof adjusted to any predetermined position, substantially as set forth.

In testimony whereof I affix my signature, in presence of two witnesses.

CHARLES H. FOSTER.
